UNITED STATES PATENT OFFICE.

EDWARD D. F. SHELTON, OF BIRMINGHAM, CONNECTICUT.

IMPROVEMENT IN PAPER BOXES.

Specification forming part of Letters Patent No. **158,134**, dated December 22, 1874; application filed November 14, 1874.

To all whom it may concern:

Be it known that I, EDWARD D. F. SHELTON, of Birmingham, in the county of New Haven and State of Connecticut, have invented a new Paper Box; and do hereby declare the following, when taken in connection with the accompanying drawings and the letters of reference marked thereon, to be a full, clear, and exact description of the same, and which said drawings constitute part of this specification, and represent, in—

Figure 1, perspective view; Fig. 2, diagram of the blank from which the box is formed; Fig. 3, perspective view illustrating the method of folding the blank; Fig. 4, vertical central section; Fig. 5, plane central section.

This invention relates to an improvement in the manufacture of paper boxes or cases; the object being to form the case from a single piece of paper closed by the peculiar cut upon all sides, save one, which is provided with a "tuck."

The blank is first cut from suitable paper or material, as in Fig. 2, the broken lines denoting the lines of fold or bend.

The two sides A A are turned up, and extremes brought together and secured, as at *a*, Fig. 3. The intermediate portion B forms one side, the two parts A A two other sides, and the parts C C unite upon the fourth side. Next, the flaps D D are turned nearly over onto the intermediate part E, as seen in Fig. 3; then the flaps F F are turned up so as to

pass within the two sides A A; then the parts D D and E are turned toward and passed in between the sides A B C until the flaps F have fully entered within the sides A, so that the part G will close that end, and form the fifth side or one end of the case, the part E completing the fourth side within the parts C. The flaps D are then turned back against the sides A, the flap H protruding at the other or open end of the box. Then the flaps I I are turned inward to close that open end, and the flaps H and L turned down over the flaps I, and the end of the flap L passed through a slot, *a*, in the flap H, as seen in Fig. 4.

This method of cutting and folding the blank produces a strong and durable case, with all the angles securely closed, and with but a single tuck.

I do not broadly claim a box made complete from one piece of material by several folds, as such, I am aware, is very old; but

I claim as my invention—

As an article of manufacture, the box herein described, consisting of a blank cut from a single piece to form the principal sides B E and A A, and the ends G I, with the auxiliary sides D D, and flaps C C, F F, and L H, folded and secured substantially as specified.

E. D. F. SHELTON.
